PATENT'S BEDEASE

Otto B. Kjos and Henry A. Korda,
Pelican Rapids, Minn.

Application January 31, 1949, Serial No. 73,746

3 Claims. (CL 5—317)

1

This invention relates to a device in aiding patients lying in beds to raise themselves to a sitting position.

An object of this invention is to provide a device for attachment to the foot of a bed which can be normally disposed in an upraised inoperative position above the bed of the patient, and can be easily swung downwardly to a substantially horizontal operative position on top of the bed and in a position whereby the patient may grasp the end of the device and pull himself upwardly to a sitting position. Another object of this invention is to provide a device of this kind which can be secured to the top rail of the foot of the bed or any point along the length of the rail, so that the handle or grip may be grasped by either or both hands of the patient.

With the above and other objects in view, my invention consists in the arrangement, combination and details of construction disclosed in the drawings and specification, and then more particularly pointed out in the appended claims.

Figure 1 is a detailed side elevation of a device constructed according to an embodiment of this invention showing the device in operative position, and showing the foot of a bed, the latter being broken away and partly in vertical section,

Figure 2 is a plan view of the device partly broken away and in section,

Figure 3 is a sectional view taken on the line 3—3 of Figure 1,

Figure 4 is a fragmentary sectional view taken on the line 4—4 of Figure 1,

Figure 5 is a fragmentary sectional view taken on the line 5—5 of Figure 1.

Referring to the drawing and to numeral 10 designated generally the foot of a bed which is provided with a top horizontally disposed rail 11. In order to provide a means whereby a patient lying on the bed may readily pull himself upwardly to a sitting position, I have provided an attachment which is adapted to be secured to the rail 11 as will be herein described, and is adapted to project lengthwise and forwardly to a position whereby the patient lying on the bed may readily grip the device for pulling himself upwardly to a sitting position. This device includes a gripping member generally designated as 12 which is formed as a C-clamp having a stationary jaw 13 carried by a horizontally disposed bar 14 adapted to fit over the bed rail 11 and is formed with a dependent arm 15 that extends below the axial center line of the rail and through which arm a threaded shaft 16 engages. The shaft 16 is provided at its inner end with a swivel mounted gripping jaw or head 17 adapted to engage the rail 11

2

and cooperate with the jaw 13 in tightly gripping the gripping member 12 onto the rail. The shaft 16 has secured to the forward end thereof a handle or knob 18 by means of which the grip may be tightened or loosened with respect to the rail 11. An elongated body 19 is adapted to slidably and pivotally engage the back of bar 14 of the clamp 12 and includes a bifurcated rear end 20 which is adapted to straddle the back 14 and the latter is formed with an elongated horizontally disposed slot 21 through which a bolt 22 slidably engages. The bolt 22 extends across the bifurcated portion of the body 19 and when the body 19 is in an operative position this body will be substantially horizontally disposed as shown in Figure 1. If it is desired to position the device in an inoperative position, the body 19 may be raised on an angle to the vertical and moved rearwardly to substantially the dotted line position shown in Figure 1, whereby the forward end 36 of the slot 21 formed in the body 19 will engage the upper edge of the back member 14, and hold the body 19 in an upraised position. The body 19 is provided with an elongated opening or bore 23 within which the rear end of an elongated rod 24 is adapted to rotatably engage. The rod 24 is formed with an annular groove 25 and a set screw 26 is threaded through the body 19 and is adapted to engage in the groove 25 to thereby hold the body 19 against endwise moving in the bore 23 while permitting rotary movement of rod 24 relative to the body 19. A second annular groove 27 is also provided in the body 19 and a second set screw 28 is threaded through the body 19 for engagement in the groove 27 and for holding the rod 24 against endwise movement. The rod 24 may be of any desired length such that the looped handle or grip 29 carried by the forward end thereof will be positioned in a convenient location for grasping by the patient when the latter is in reclining position.

A second handle or grip 30 is adjustably carried by the rod 24 being formed with a shank 31 which is pivotally mounted between the arms 32 of the sliding block 33 having an opening 34 within which the rod 24 engages. A pivot bolt 35 extends through the ears 32 and through the shank 31 to thereby pivotally secure the shank 31 to the block 33. Preferably as shown in Figures 1 and 2 the bolt 35 engages through the shank 31 in a position whereby the shank 31 will be slightly tilted when the handle 30 is grasped and raised upwardly a slight degree so that the block 33 will be locked by biting engagement of the ends of the opening 34 with the rod 24.

In the use and operation of this device the

clamp 12 is secured to the bed rail 11 at any selected position along the length of this rail so that the patient may grasp the handle or grip 29 with either or both hands. When the device is not used, the rod 24 with the coupling member or body 19 is raised upwardly at an angle to the vertical and pushed rearwardly to substantially the dotted line position shown in Figure 1. In this inoperative position the inner end of the slot formed by the bifurcations 20 will engage the upper edge of the bar 14 and hold the rod 24 in an upwardly and forwardly inclined position. When the patient desires to pull himself upwardly to a sitting position the rod 24 with the coupling member 19 may be pulled forwardly with respect to the clamp 12 until the pivot bolt 22 is at the forward end of the slot 21. At this time the rod 24 will be lying on top of the bed with the handle or grip 29 conveniently located with respect to the patient's hand or hands. The patient may then brace himself by his feet placed against the foot of the bed and pull himself upwardly to a sitting position by gripping the handle or grip 29. It is not, however, necessary for the patient to brace himself by his feet, as the patient can also pull himself up to a sitting position merely by gripping the handle or grip 29 and exerting the necessary pull. The intermediate or adjustable grip 30 may be alternately or optionally used either at the beginning of the pulling operation or when the patient is partially raised and desires a shorter grip with respect to the rod 24.

I do not mean to confine myself to the exact details of construction herein disclosed but claim all variations falling within the purview of the appended claims.

What is claimed is:

1. A device for attachment to the foot of a bed to aid a reclining person to sit up comprising a C-clamp having a straight back portion and adapted to be clamped over the upper rail of the foot of the bed, an elongated rod, a hand

5

grasp carried by one end of said rod, and a transverse member carried by an end opposite from said one end of the rod and engaging with said straight back portion for pivotally securing the other end of said rod to the back of the clamp.

10

2. A device for attachment to the foot of a bed to aid a reclining person to sit up comprising a C-clamp adapted to be clamped onto the upper rail of the foot of the bed, the back of said clamp having a longitudinally disposed elongated opening, an elongated rod, a hand grasp at one end of said rod, and means carried by said rod and loosely engaging through said opening for pivotally and slidably securing said rod to said clamp.

15

3. A device for attachment to the foot of a bed to aid a reclining person to sit up, comprising a C-clamp adapted to be clamped onto the upper rail of the foot of the bed, said C-clamp being formed with a longitudinally extending slide means, an elongated rod, a hand grasp carried by one end of said rod, a transverse member carried by said rod and engaging with said slide means for pivotally securing the other end of said rod to said clamp, a second hand grasp, and means securing said second hand grasp to said rod for endwise adjustment therealong.
